UNITED STATES PATENT OFFICE.

DAVID A. COOK, OF LAMONT, IOWA.

MILK-COOLING DEVICE.

1,427,443.

Specification of Letters Patent. Patented Aug. 29, 1922.

Application filed April 22, 1921. Serial No. 463,670.

To all whom it may concern:

Be it known that I, DAVID A. COOK, a citizen of the United States, residing at Lamont, in the county of Buchanan, State of Iowa, have invented certain new and useful Improvements in Milk-Cooling Devices; and I do hereby declare the following to be a full, clear, and exact description of the invention, such as will enable others skilled in the art 10 to which it appertains to make and use the same.

This invention relates to new and useful improvements in cooling devices and particularly to devices for cooling milk.

15 One object of the present invention is to provide a novel and improved device whereby the milk, drawn from the cow, can be immediately cooled, in a can or in a bucket, before being poured into the can.

20 Another object is to provide a novel and improved structure of this character which is adapted for ready application to or removal from the milk buckets or cans thus rendering it easy to use the device in one bucket or can and then remove it and use it 25 in another bucket or can.

A further object is to provide a novel and improved device of this character which, when applied to the bucket or can filled with 30 milk, will permit cold water to pass therethrough to cool the milk.

35 A still further object is to provide a novel and improved device of this character which is capable of being applied to the bucket or can and rocked back and forth, within the milk, while at the same time cold water is contained in the device or is flowing therethrough.

40 Other objects and advantages will be apparent from the following description when taken in connection with the accompanying drawing.

In the drawing:

Figure 1 is a side elevation of a milk 45 bucket showing the invention attached therein.

Figure 2 is a top plan view of the bucket slightly reduced showing the position of the device.

50 Figure 3 is a vertical transverse sectional view through the bucket, taken on the line 3-3 of Figure 2, showing the invention in side elevation.

Referring particularly to the accompanying drawing, 10 represents a milk bucket which has the diametrically opposite open-

ings 11 and 12, near the upper end thereof, the purpose of which will presently appear.

The cooling device comprises a substantially U-shaped pipe 13 which is disposed 60 within the bucket with its ends uppermost. The smaller end 14 is turned outwardly and downwardly to extend over the upper edge of the bucket, as shown at 15, while the other end extends vertically upward above the 65 bucket and at the other side, in the form of a funnel 16. On the outer face of the funnel there is mounted a handle 17. Secured to the leg of the pipe 13, below the funnel, and within the bucket, is an upwardly and outwardly inclined resilient arm 18, the upper end of which is turned outwardly, as at 19 and is disposed through the opening 11 of the bucket. Secured to the other leg of the pipe 13, and also within the bucket, is an upwardly and outwardly inclined resilient arm 70 75 20, the intermediate portion of which is bent to form an outwardly extending lug 21 disposed in the other opening 12 of the upper end of the bucket. The portion of the arm 20, above the lug, extends above the portion 15 of the first leg, and above the upper edge of the bucket, to provide a handle 22 which is to be grasped to flex the arm inwardly and disengage its lug 21 from the opening 12, 80 85 when the device is to be removed from the bucket.

It will be noted that the end 19 and the lug 21 are disposed in the same plane, and when engaged in the openings 11 and 12, 90 of the bucket, serve as trunnions for the pipe 13, and when the handle 17 is grasped the pipe can be rocked or swung within the bucket, with the result that the portion of said pipe which is within the milk will be 95 moved back and forth through the milk and cause the rapid cooling of the same. To aid the cooling of the milk, water of a low temperature is poured into the pipe 13, through the funnel. This may be arranged 100 so that a continuous flow of cold water is maintained through the pipe, thus producing the proper reduction of temperature in a shorter time than when a certain quantity of water is placed in the pipe and the same 105 rocked back and forth.

By means of the flexing of the arm 20, the device is readily removable from one bucket and applied to another, with the result that a single person can quickly cool a large 110 quantity of milk, within a short space of time, and without any great amount of labor.

There is thus provided a novel and simple device whereby dairymen can easily and quickly remove the animal heat from the milk as soon as the milk is drawn from the cow, with the result that the milk will keep in a pure and wholesome condition for a much longer time than otherwise. Also, the bacteria, in the milk, will be prevented from multiplying as rapidly as they would were the milk retained any length of time before being cooled.

The fact that the device can be easily and quickly applied to and removed from the milk bucket, renders the device one which can be handled with facility and economy, thus doing away with the usual expensive cooling systems generally required.

While I have shown the device used in connection with a milk bucket, I wish it understood that other receptacles may be used with the same results, as for instance the large five or ten gallon milk cans. In the latter case larger quantities of milk can be cooled at one time.

25 What is claimed is:

1. In a milk cooling device, the combination with a receptacle having diametrically opposite openings in the upper end, of a

U-shaped conduit disposed in the receptacle for rocking movement, and resilient means 30 on the legs of the conduit for detachably engaging in said openings and supporting the conduit in position for such rocking movement.

2. In a milk cooling device the combination with a receptacle having openings adjacent the upper end, a U-shaped pipe disposed vertically in the receptacle, said pipe being arranged to receive a cooling medium therethrough, a handle carried by the upper 40 end of one of the legs of the pipe, a flexible arm secured to said leg and having a lug journaled in one of said openings, and a second resilient arm carried by the other leg of the pipe and formed with a lug journaled in the other opening whereby the pipe is capable of rocking movement in the liquid in the receptacle, and ready removal from the receptacle upon flexing the last-named arm to release the lug from the opening.

45 In testimony whereof, I affix my signature, in the presence of two witnesses.

DAVID A. COOK.
